UNITED STATES PATENT OFFICE

155,290

DESIGN FOR AN AUTOMOBILE HEADLIGHT VISOR

William H. Johnsen, Dallas, Tex.

Application June 27, 1949, Serial No. 3,567

Term of patent 14 years

(Cl. D48—32)

To all whom it may concern:

Be it known that I, William H. Johnsen, a citizen of the United States, residing at Dallas, in the county of Dallas and State of Texas, have invented a new, original, and ornamental Design for an Automobile Headlight Visor, of which the following is a specification, reference being had to the accompanying drawing, forming part thereof.

Figure 1 is a front perspective view of an automobile headlight visor, showing my new design.

Figure 2 is a bottom plan view.

Figure 3 is a top plan view thereof and

Figure 4 is a side elevational view.

I claim:

The ornamental design for an automobile headlight visor, substantially as shown.

WILLIAM H. JOHNSEN.
